UNITED STATES PATENT OFFICE

166,943

STOCKING

John A. Beck, Perkasie, Pa.

Application August 15, 1951, Serial No. 16,294

Term of patent 14 years

(Cl. D47—7)

To all whom it may concern:

Be it known that I, John A. Beck, a citizen of the United States, residing at Perkasie, in the county of Bucks and State of Pennsylvania, have invented a new, original, and ornamental Design for a Stocking, of which the following is a specification, reference being had to the accompanying drawing, forming part thereof.

Figure 1 is a perspective view of a stocking as the same would appear when worn on a leg, and embodying the design of my invention.

Figure 2 is a rear view of the lower portion of the stocking as the same would appear when worn on a leg, and embodying the design of my invention.

I claim:

The ornamental design for a stocking, as shown.
JOHN A. BECK.
